Warren W. Pitts' Cotton-Ploughing Machine
Letters Patent

The Schedule referred to in these Letters Patent and making part of the same containing a description in the words of the said Warren W. Pitts himself of his improvement in the machine for ploughing and thinning out cotton

Be it known that Warren W. Pitts, of Wilsonville, County of Shelby, and State of Alabama have made an improvement, being a machine for ploughing and thinning out cotton, called Pitts Cotton Cultivator, which is described as follows, reference being had to the annexed drawings of the same, making part of this specification. This machine is constructed in the following manner. Two wheels A, B, two feet six inches in diameter are prepared & may be composed of plank three fourths of an inch thick. These wheels are to be permanently attached to a hub or circular solid piece of timber or iron C, ten inches in diameter, from seven to ten inches long, the iron axle less, D, turned true at the ends is to pass through the centre of the wheels (and hub), and to project out from the wheels on either side two inches. These wheels thus united are placed between a rectangular frame to the sides of which are composed of swelling two feet five inches long and two and a half inches thick by three wide. One foot from the ends of these pieces, are the bearings of the axle less. The axle runs into the frame one inch and a half, so as to leave a small space between the wheels and the frame. At the ends of these pieces in which the axle is inserted are framed two foot pieces E, projecting forward at an angle of forty five degrees more or less, and extending to the ground at the bottom of these pieces are attached ploughs F, one to each made as an ordinary dragon plough with the working edges turned toward each other, and so formed as to run on a line with the inside of each wheel, so that the wheels will follow in the furrow they make. The two inlaid foot pieces will be joined together by a piece of timber G, the same size with themselves, a little below where they join the side pieces so as to add to their strength and to keep them a proper distance apart. A similar piece H will unite the side pieces in which the axle run immediately behind the wheels. The beam I to which the horse will be attached will be placed between the wheels and connected to

3-31-1836

an upright piece K, which itself is tenanted to the cross piece that unites the hindmost part of the frame. The beam may be of any convenient length, say four and an half or five feet long and attached in front of the wheels to the cross piece uniting the inclined foot pieces by means of an iron rod and screw L. The handle M will be fastened to the side pieces and connected to a cross piece running through the end of the beam. A zigzag groove N will be formed around the hub to which the wheels are attached about an inch wide, an inch deep. Two short iron bolts O, will be inserted through the beam, between the hub and the plough, and fastened to it by screws and caps on top of the beam. These bolts will have holes in the bottom of them, in which will be inserted the end of a crank P, to be constructed after the following manner: viz. the point will turn in the holes in the bolts, & it will be so placed under the beam that its end marked Q will fit into & be controlled by the zigzag groove in the hub. This will give the point R a transverse motion. To the point R a hoe with the helve inserted through the centre must be attached. It is planned horizontally, & formed so as to cut both ways, of any size that may be desired. It will be attached by means of a screw and bolt & made with a space in the helve of the hoe so that it can be raised or lowered at pleasure. The horse may walk on the ridge, or by pulling on a iron windlass to the beam, or carrying it the horse may be made to walk on one side. By having one or more hoes of different sizes, any quantity of the cotton required may be cut out. This machine may likewise be used for other purposes. See for the illustration of my invention. Refer to the model of the same deposited in the Patent Office. What I claim as my invention and which I desire to secure by Letters Patent consists in the machine for ploughing and thinning out cotton, called "Pitt's Cotton Cultivator" as before described.
